US0D1025200S

(12) **United States Design Patent** (10) **Patent No.:** **US D1,025,200 S**
(45) **Date of Patent:** **** Apr. 30, 2024**

(54) **TYPEFACE**

- (71) Applicant: **Truist Bank**, Charlotte, NC (US)
(72) Inventors: **Bianca Berning**, Bromley (GB); **Rafael Saraiva Soares**, Rio de Janeiro (BR)
(73) Assignee: **Truist Bank**, Charlotte, NC (US)
(**) Term: **15 Years**
(21) Appl. No.: **29/906,697**
(22) Filed: **Nov. 8, 2023**

Related U.S. Application Data

- (63) Continuation of application No. 29/881,805, filed on Jan. 6, 2023, now Pat. No. Des. 1,011,415, and a continuation of application No. 29/777,752, filed on Apr. 8, 2021, now Pat. No. Des. 978,962.
